US00D922724S

(12) **United States Design Patent** (10) **Patent No.:** **US D922,724 S**
(45) **Date of Patent:** **** Jun. 15, 2021**

(54) **AUTOMATED TELLER MACHINE**

(71) Applicant: **A-to-Be Mobility Technology S.A.,**
São Domingos de Rana (PT)

(72) Inventor: **Tiago Querido da Silva Girão, São**
Domingos de Rana (PT)

(73) Assignee: **A-to-Be Mobility Technology S.A.,**
São Domingos de Rana (PT)

(**) Term: **15 Years**

(21) Appl. No.: **29/706,918**

(22) Filed: **Sep. 25, 2019**

(30) **Foreign Application Priority Data**

Apr. 17, 2019 (EP) 06380002-0002

(51) **LOC (13) Cl.** **99-00**

(52) **U.S. Cl.**

CLAIM

The ornamental design for an automated teller machine, as shown and described.

DESCRIPTION

FIG. 1 is a front perspective view of an automated teller machine, showing my new design;

FIG. 2 is a front view thereof;

FIG. 3 is a right-side view thereof;

FIG. 4 is a left-side view thereof;

FIG. 5 is a rear view thereof;

FIG. 6 is a top view thereof; and,

FIG. 7 is a bottom view thereof.

The broken lines shown in the figures illustrate portions of the automated teller machine that form no part of the claimed design.

1 Claim, 7 Drawing Sheets
